UNITED STATES PATENT OFFICE

DANIEL T. FINKBEINER, OF BEAVER, PENNSYLVANIA

FENCE SUPPORTING DEVICE

Application filed August 8, 1931. Serial No. 555,995.

This invention is a device for supporting fences, and more particularly fences of the flexibly-connected-picket type, although not limited to use in connection with this particular character of fencing.

One of the objects of the invention is to provide a simple and inexpensive means by which the weight of the fencing may be adequately supported, and in such a manner as to eliminate wire wear and breakage due to torsion and abrasion while the fencing is in use. A further object is to provide means which will greatly facilitate the erection of fencing, and which will permit the use of shorter fence posts than those now commonly required. A further object is to provide means for supporting snow fencing and similar flexible structures without necessity of wiring the fence pickets to the posts, as is now common practice. A further object is to provide means for so supporting the fencing that the entire weight of the structure concentrates at a position located a short distance above the ground line, thereby lowering the center of gravity or force thrust on the post, and avoiding the supporting of the weight by hooking the longitudinal wire strands to lugs or hooks projecting from the posts.

The invention will be hereinafter fully set forth and particularly pointed out in the claims.

In the accompanying drawings:

Figure 1 is a front elevation illustrating a portion of a snow fence, and means for supporting the same constructed in accordance with the invention. Figure 2 is a cross section on the line 2-2, Figure 1. Figure 3 is a cross sectional view on the line 3-3, Figure 1. Figure 4 is a perspective view illustrating the fence supporting stirrup. Figure 5 is a similar view of the fence steadyng clamp. Figure 6 is a view illustrating a slight modification. Fig. 7 is a perspective view showing a slight modification of the fence supporting stirrup as shown in Figure 6.

Referring to the drawings, P designates a fence post which may be of any preferred construction. For purposes of illustration, the same is shown as constructed of steel of

channel shape in cross section and provided with marginal flanges 10.

Mounted on the fence post near the lower end thereof is a fence supporting stirrup S, which is preferably constructed of sheet metal bent into channel form to provide sides 11 and 12 respectively. Portions of the one side, such as the outer side 12 are cut as indicated at 13, and bent inwardly at right angles to engage the wall 11, so as to form relatively spaced adjacent abutment walls 14, as shown. The portion of wall 11 between the abutment walls 14 constitutes a supporting portion 15, which is provided with an opening 16 to receive a rivet 17, by means of which the stirrup S is pivotally secured to the post P. The fencing, which for purposes of illustration is shown as in the form of a common type of snow fencing now in general use, is usually constructed of spaced apart pickets 18, which are flexibly connected by twisted wire strands 19, as shown in Figure 1. Said member C, by reason of its design is flexibly rigid at the abutment shoulders 26, so as to withstand the twisting and winding due to the torsional stresses which may be set up by storm-fence-swaying conditions on either fence panel adjacent to the post.

In practice, the stirrup S is secured to the post P at a position approximately corresponding with the planes in which the lower ends of the pickets 18 are to be maintained while the fence is in use, and the abutment walls 14 are so arranged as to provide two spaced apart pockets X each capable of receiving the lower end of a picket 18. In operation, two adjacent pickets are located in the respective pockets X, so as to be supported by the stirrup, said two pickets being equally spaced on opposite sides of the supporting portion 15. By this arrangement, the weight of the fence is carried by the stirrup S, and by reason of the pivotal mounting of said stirrup will permit of a certain amount of flexibility in stringing the fencing from post to post, so that said fencing may conform to the ground contour.

The upper part of the fencing may be held in place in any suitable manner, for instance, the upper strand wires 19 may be hooked

over lugs 20 carried by the fence post as illustrated in Figure 6, thereby steadyng the fence, although sustaining no part of the weight thereof.

5 Or, in lieu of this method, the fencing may be steadied by a clamp member C, as illustrated in Figures 1, 3 and 5. Referring to said figures, said clamp member consists of a post-engaging portion 25, from which project 10 forwardly extended abutment shoulders 26, which are joined with laterally positioned resilient clamping arms 27, slightly offset, so that they will grasp the same pickets 18 which are engaged by the pockets X of the stirrup 15 S. The post-engaging portion is provided with a central opening 28 through which a rivet 29 is passed, to pivotally secure the same to the post P. It will also be noted that the 20 picket engaging arms 27 are provided with struck-in portions 30 constructed to embed themselves into the wood of the pickets, and thereby insure a more perfect engagement between said arms 27 and said pickets.

25 In practice, the posts are set up in the usual manner, it being preferred to have each one previously equipped with the stirrup S and the clamp C, so that in setting up the fencing two adjacent pickets, at positions opposite the post P may have their lower ends seated 30 in the pockets X of the stirrup S, the clamp C at this time being swung around to a position parallel with the fence post, so as to pass between said two adjacent pickets, and permit ready engagement of the pickets with the stirrup. After the pickets have been engaged with the stirrup, the clamp member C 35 may be swung around into horizontal position, the arms 27 being sufficiently resilient to pass over the pickets 18, and their resilient 40 character being such as to firmly hold the same pickets in an upright position. By this arrangement, the weight of the fence is carried by the pickets which rest in the stirrups, the clamps C retain the fence in a vertical 45 position, and no strain is brought upon the wires 19 to support the fence. As illustrated, the fence pickets are set into the supporting stirrup member S, and then held in place at the top by means of the clamp member C. 50 The fence picket is not held vertically but inclines at a slight angle due mainly to the space between the pickets allowing the top portions of the fence to pass rearwardly beyond the front face of the post. This rearward movement is stopped by virtue of contact of the fence wire strands against the post. This slight angle has a tendency of 55 pressing the lower front edge of the picket 60 against the inside of the front support wall of the stirrup which wall serves to hold the picket in place. By reason of this arrangement, a friction resistance is set up which in combination with the weight of the fence resting in the shoe and the cooperation of the

spring catch holds the fence from tilting or toppling over.

65 If it is desired to use the device for attaching fence to posts of the old type, such for instance those which are provided with lugs 20, the stirrup member S may be attached to the posts after they are set up, or the form of the device illustrated in Figure 6 70 may be employed. As shown in said figure, the stirrup S' is identically the same as that illustrated in Figures 1, 2 and 4, with the exception that the supporting portion 15 is provided with an arm 15' in which is formed two holes 31 and 32 respectively. The first 75 mentioned hole 31 is designed to engage a common type of rivet pin or lug 20, attached to fence posts of a type now in common use, so that the stirrup S' will be supported by the tongue 15'. The hole 32 is of somewhat different shape to engage a different "rabbet" type of lug which is also in common use. Whichever form of lug the fence post may be equipped with, the proper hole 31 or 32, as the case may be, is hooked thereover, and the stirrup is thus movably 80 supported in position. The wire strands 19 located above the plane of the stirrup may then be hooked over the correspondingly positioned lugs in the post, as shown in Figure 85 6. It will be noted, however, that the fencing will be held by the stirrup at sufficiently high elevation to maintain the wire strands out of contact with the lower portions of the hooks or lugs, so that at no time does the weight of the fencing come upon said wires. 90 In this arrangement, the wires merely serve as stays to maintain the fencing in its vertical position.

95 Should conditions arise which would make it impossible to sink the posts deep enough, for instance, where the ground is very hard, the stirrup S would normally be supported too high for efficient operation of the fence. In this event a clamp member C substituted 100 for each stirrup, or a plurality of clamp members may be used. Such clamp members will firmly and tightly retain the pickets in place, longitudinal movement of the fence being minimized by the shoulders 26. By this arrangement the fencing may be held at any 105 desired height, vertical movement being limited by the distance between the rivet 29 and the wire strands 19, because the wire strands cannot pass the clamp, and in this way the height of the snow fence from the ground may 110 be regulated.

115 The advantages of the invention will be readily understood by those skilled in the art to which it belongs. For instance, an important advantage is that by supporting the 120 weight of the fencing by means of the stirrup 125 flexibly attached to the post, the weight and wear is removed from the wires which are employed to connect the pickets, thereby eliminating wire wear and breakage due to tor- 130

sion or abrasion caused by swinging of the fence in the wind and other causes of vibration incident to service. A further advantage is that the stirrup greatly facilitates the 5 erection of the fence, and also permits the use of shorter posts, because the wires are not utilized as a part of the supporting means. Another important advantage is that by providing the stirrup and the clamp with the 10 abutment shoulders, said shoulders firmly anchor the fence pickets to which they are engaged, so that the fence may be tightly stretched between posts, the abutment shoulders serving to provide the necessary resistance 15 to movement in both directions during the stretching operation. It will also be readily understood that an important advantage is gained by placing the supporting stirrup at a short distance above the 20 ground, because by this arrangement the center of gravity or force thrust on the post is considerably lower, thereby greatly improving the stability of the fence. By constructing the clamp members with spring arms having 25 struck in portions, the fencing will not readily become disengaged from the posts, in the event that the fence and posts are blown over, either partially or entirely, while the ground is soft and the posts unstable, particularly 30 during high winds.

Having thus explained the nature of the invention and described an operative manner of constructing and using the same, although without attempting to set forth all of the 35 forms in which it may be made, or all of the forms of its use, what is claimed is:

1. A fence supporting device of the character described comprising a stirrup member having a supporting portion at the middle 40 thereof, and elongated pocket engaging pockets on opposite sides of said supporting portion, said pockets each having a bottom wall and side walls so constructed and arranged as to provide suspension means for receiving 45 the lower ends of adjacent fence pickets.

2. A fence supporting device of the character described comprising a stirrup member having a supporting portion at the middle thereof, and elongated pocket portions on 50 opposite sides of the supporting portion, said pockets each having a bottom wall, an abutment wall and side walls so constructed and arranged as to provide suspension means for receiving the lower ends of adjacent fence 55 pickets.

3. A fence supporting device of the character described comprising a stirrup member having parallel side walls, the middle portion of one wall having parts thereof bent back to 60 provide adjacently positioned spaced apart abutment walls, the other side wall having a middle supporting portion.

4. A fence supporting device of the character described comprising a stirrup member 65 having a supporting portion at the middle

thereof, said supporting portion having a supporting strip extending upwardly therefrom and provided with an opening therein for engagement with a fence lug, said stirrup member also having elongated pocket engaging portions on opposite sides of the supporting portion. 70

5. In a fence supporting means, a clamp member having an intermediate post engaging support and oppositely extended pocket engaging arms offset with respect to said support, each arm having one end joined with the support and the other end free, so that said arms may yieldably engage the face of a fence 75 picket.

6. In a fence supporting means, a strip-like clamp member of flat metal having an intermediate post engaging support, and oppositely disposed abutment shoulders integral therewith, said clamp member also having oppositely extended pocket engaging arms, each arm having one end integrally joined with an abutment shoulder and the other end free, so that said arms may yieldably engage 80 the face of a fence picket. 85

7. The combination with a fence post, of a stirrup member provided with pockets each pocket having a bottom wall and side walls so constructed and arranged as to provide suspension means for receiving the lower ends 90 of adjacent fence pickets, means for movably connecting said stirrup member with a fence post, and means for clamping the upper parts of said pickets to said fence post. 95

8. The combination with a fence post, of a stirrup member having a supporting portion at the middle thereof and elongated pockets positioned on opposite sides of said supporting portion, said pockets each having a bottom wall and side walls so constructed and arranged as to provide suspension means for receiving the lower ends of adjacent fence pickets whereby the fence may be accommodated to variations of ground contours, means for movably connecting the stirrup member with the fence post, and means for clamping the upper parts of said pickets to said fence post. 100 105 110

9. The combination with a post and a fence provided with spaced apart pickets, of a stirrup having spaced apart pockets for receiving the lower ends of a plurality of adjacent fence pickets so as to support the fence, means for pivotally connecting said stirrup to the post, and clamping means carried by the post and positioned to engage the pickets which are engaged by said stirrup. 115 120

10. The combination with a fence post and a fence provided with spaced apart pickets, of a stirrup supported by said post and having means for engaging the lower ends of a plurality of adjacent fence pickets, so as to support the fence, and a clamp member movably connected with said post and having 125 130

means for yieldably engaging said adjacent fence pickets.

11. The combination with a post and a fence formed with a plurality of spaced apart pickets, of a stirrup having parallel side walls, the middle portion of one wall being bent to provide spaced apart abutment walls, and pockets positioned to engage a plurality of adjacent fence pickets so as to support the same, said stirrup having a middle supporting portion engaging said post, and clamping means connected with said post and positioned to engage the upper portions of said adjacent pickets.

12. The combination with a fence post and a fence formed with a plurality of spaced apart pickets, of a stirrup supported by said post and having means for engaging the lower ends of a plurality of adjacent fence pickets, so as to support the same, and a clamp member movably connected with said post and having means for yieldably engaging said adjacent pickets.

13. The combination with a fence post and a fence formed of a plurality of spaced apart pickets, of a stirrup supported by said post and having means for engaging the lower ends of a pair of adjacent fence pickets, so as to support the fence, and a clamp member connected with said post and having resilient arms positioned to engage the upper portions of said pair of pickets, said stirrup and said clamp member having abutment shoulders positioned to limit longitudinal movement of the fence.

14. In a fence supporting means, a clamp member having a post-engaging portion and laterally extended resilient arms positioned to engage two adjacent fence pickets, said arms being offset with respect to said post-engaging portion and having struck-in portions for penetrating said pickets.

In testimony whereof I have hereunto set my hand.
